UNITED STATES PATENT OFFICE.

JOHN BALLOU, OF SOMERVILLE, MASSACHUSETTS.

NECKTIE-FASTENER.

SPECIFICATION forming part of Letters Patent No. 352,109, dated November 9, 1886.

Application filed May 19, 1886. Serial No. 202,688. (No model.)

To all whom it may concern:

Be it known that I, JOHN BALLOU, of Somerville, county of Middlesex, and State of Massachusetts, have invented certain Improvements in Necktie-Fasteners, of which the following is a specification.

This invention relates to a device for securing a necktie upon the person of the wearer; and it consists in the employment of a hook secured to the necktie and adapted to engage with the neckband of the collar or shirt, and used in connection with an elastic loop or spring, or without such loop or spring.

In the drawings accompanying, in which similar letters refer to similar parts, Figure 1 shows a general perspective view of the device; Fig. 2, a sectional view; Fig. 3, a plan view of the shield or base frame of a necktie.

A represents a shield or base-frame of a necktie of a common form. B is a hook, to which is secured an elastic loop, c. The bight of the loop c is passed through the holes d and e in the shield A, and over the hook, resting in the throat of the hook, with the point of the hook outward from the shield.

In attaching the necktie to the person, the hook being at the upper edge of the tie and turned inward, it is permitted to hook over the neckband of the collar or shirt, and thus the tie is held in its proper place, the elasticity of the loop permitting the proper adjustment of the tie.

The distinguishing characteristic of this device is the hook attached to the shield in a manner to permit its adjustment in a direct 35 vertical line, or a line transversely with the shield, and with only slight lateral motion, and this is produced by attaching the elastic to the lower part of the hook, then passing the bight through the holes d and e, and the loop finally 40 over the throat of the hook, as at i, and thus the hook is held to the tie and with the results described.

I am aware that a hook elastically secured to a necktie has been employed with substantially the object for which I employ it. Therefore I do not claim, broadly, the use of a hook elastically secured to the necktie; but

I claim—

A necktie-fastener consisting of a hook secured by an elastic connection to the shield, the elastic consisting of a loop secured to the lower end of the hook, the bight of the loop being passed through apertures in the shield and over the throat of the hook, all arranged as described, to permit of motion of the hook chiefly in a line transversely of the shield, substantially as and for the purpose shown.

JOHN BALLOU.
